UNITED STATES PATENT OFFICE.

WILLIAM E. SHERBONDY, OF CLEVELAND, OHIO.

SPARK-PLUG.

1,224,423.

Specification of Letters Patent. Patented Apr. 24, 1917.

Application filed August 19, 1916. Serial No. 115,761.

To all whom it may concern:

Be it known that I, WILLIAM E. SHERBONDY, a citizen of the United States, residing at Cleveland, in the county of Cuyahoga and State of Ohio, have invented certain new and useful Improvements in Spark-Plugs, of which the following is a specification.

This invention relates to spark plugs, the object of the invention being to provide an improved spark plug, simple in construction, durable and unusually efficient in use; in which the insulating porcelain will be effectively protected against injury or breakage; in which also the short circuiting of the ordinary plug between the terminal at the top thereof and the bushing or shell by moisture or otherwise is prevented, and in which also the conduit wire is not connected directly with the top of the central electrode, whereby certain advantages are obtained.

In the drawings accompanying and forming a part of this specification Figure 1 is a side view of this improved spark plug; Fig. 2 is a vertical sectional view thereof; Fig. 3 is a cross-sectional view taken in line 3—3 of Fig. 2; and Fig. 4 is a top view of the plug.

Similar characters of reference indicate corresponding parts in the different figures of the drawings.

Spark plugs as ordinarily constructed comprise a metal shell threaded to be turned into the head of a gas engine and this shell carries an outer terminal wire and an inner terminal wire insulated from the shell usually by porcelain. This porcelain projects above the top of the shell for the connection of the conduit wire to the central electrode at the top of the porcelain, and this projecting portion of the porcelain is frequently broken or cracked, either accidentally or through carelessness when placing the plug in the engine or removing it for cleaning purposes, requiring the plug to be entirely disassembled and the substitution of a new porcelain. Moreover it has been the practice to make this projecting portion of the porcelain of quite some length, which, of course, increases the liability of breakage. Frequently by reason of moisture or oil on the outside of the porcelain or core short circuiting between the shell and the upper projecting portion of the central electrode takes place. It is also well understood that a small deposit of carbon on the inside walls of the shell and around the porcelain core

not infrequently forms a circuit to the central electrode thus causing a short circuit, so that the plug becomes foul and useless.

The present improvement overcomes these several disadvantages because it permits the use of a very short porcelain core above the bushing and also protects that short core not only from breakage and cracking but from moisture.

In the preferred form thereof herein shown and described this improved spark plug comprises a hexagonal shell 2 centrally bored for the reception of the insulator or porcelain 3 carrying the central electrode 4. This shell has the usual chamber or petticoat 5 formed at the lower end thereof around the central electrode and carries at such lower end the outer terminal or wire 6 and is also provided with the proper threads to enable the shell to be turned into the head of the engine. The upper end of the shell is provided with a chamber 7 interiorly threaded as at 8, and into this chamber the upper end of the porcelain projects, the porcelain being held within the shell by a suitable bushing 9 turned into the threaded bore of the shell at the lower end of the chamber. This chamber is of sufficient size to permit the bushing to be turned into position or removed as occasion should require.

Carried by the upper end of the shell and closing the chamber is a threaded closure or plug 10 of suitable insulating material. This closure carries a terminal rod or wire 11 located to form a spark gap 12 between its lower end and the top of the central electrode. The upper projecting portion of this rod is threaded for the reception of the usual nuts 13 by means of which the conduit wire is connected with the closure or plug. The shell adjacent to the spark gap 12 is provided with suitable openings which may be closed by mica or other transparent material located around the inner wall of the chamber and through which the spark at the gap may be readily seen.

From the foregoing it will be observed that this improved plug has a chamber at both ends of the core or porcelain the lower one forming the usual petticoat and the upper one forming a protecting medium for the upper end of the porcelain, which thus terminates within the shell, and by reason of the present improvement this porcelain need project only a short distance beyond its bushing, just sufficient to insulate the

upper end of the central electrode carried by the core or porcelain from the bushing. By the present improvement it will also be observed that the conduit wire is connected with the plug or closure of the shell and not directly with the central electrode as is usual heretofore, so that the tightening of the nuts on the rod 11 does not in any way tend to move or shift the central electrode.

10 It is the usual practice of a mechanic before placing the plug in the engine to make sure that the spark gap at the lower end of the plug is the proper one, this being in many instances about a thirty-second of an 15 inch, and frequently it is necessary to bend one of the spark gap wires toward or from each other, whichever happens to be the easiest for the mechanic, so that it is not infrequent to bend the central electrode wire 20 toward the outer shell wire. In consequence when the conduit wire is connected to the upper end of the central electrode or wire the turning of the nuts has a tendency to cause the central wire to rotate in the core or 25 porcelain so that if the central wire has been bent toward the outer or shell wire before the plug has been placed in the engine the rotating of the central wire by turning the clamping nuts when the conduit wire is connected 30 to the upper end of this central wire causes the central wire sometimes to rotate toward or from the central wire so as to increase or decrease the spark gap between the terminal wires and put the plug out of 35 commission. The user, however, does not know this until he attempts to run his engine and even then it requires some time to find out what is wrong, not expecting trouble from the spark plug, especially if he has just 40 placed a new one in the engine. By the present improvement, however, there is no possibility of turning the central wire, since the conduit wire is not connected therewith, but is connected with the rod in the closure 45 or plug which has no direct connection with the central electrode carried by the porcelain.

By forming a spark gap at the upper end of the porcelain greater resistance is also offered to the current so that it is intensified and this causes the spark to jump the gaps with greater efficiency.

In addition to the foregoing the formation of the protecting chamber around the upper end of the core or porcelain enables the shell to be made with a long hex which very materially facilitates the use of a wrench in removing and replacing the plug in position in the engine.

60 The insulated plug hereinbefore referred to is provided with a knurled edge 14 whereby it may be readily turned into and out of the shell and by loosening the clamping nut connecting the conduit wire with this plug 65 the plug itself may be removed without the

necessity of removing the terminal wire from the plug if desired.

The various details may be more or less changed without departing from the spirit or scope of this improvement.

70

I claim as my invention:

1. A spark plug comprising a one-piece long hex shell having an exteriorly threaded lower end and an interiorly threaded chamber at its upper end, an insulating core 75 carried by said shell and projecting into and terminating within said chamber and carrying a central electrode, an insulating plug threaded into said chamber and carrying means for connecting a conduit wire with 80 said electrode.

2. A spark plug comprising a one-piece long hex shell having an exteriorly threaded lower end and an interiorly threaded chamber at its upper end, an insulating core carried by said shell and projecting into and terminating within said chamber and carrying a central electrode, an insulating plug 85 threaded into said chamber and carrying means for connecting a conduit wire with 90 said electrode, said means spaced from the central electrode to form a spark gap, said shell having adjacent to said spark gap one or more openings therein.

3. A spark plug comprising a one-piece 95 long hex shell having an exteriorly threaded lower end and an interiorly threaded chamber at its upper end, an insulating core carried by said shell and projecting into and terminating within said chamber and carrying a central electrode, an insulating plug threaded into said chamber and carrying means for connecting a conduit wire with 100 said electrode, said means spaced from the central electrode to form a spark gap, said shell 105 having adjacent to said spark gap one or more openings therein, and transparent material located in said chamber and covering said opening or openings.

4. A spark plug comprising an integral 110 shell having a relatively long hex on its exterior and an exteriorly threaded chamber at its lower end and an interiorly threaded chamber at its upper end, said chambers having a communicating bore having an annular 115 shoulder, an insulating core having a shoulder in juxtaposition to the shoulder of the bore and having its ends projecting into and terminating within said chambers, the bore adjacent to the upper chamber being 120 interiorly threaded, a bushing within said upper chamber and fitting said bore threads for holding the insulating core in position and an insulating plug closing the upper chamber and carrying a rod for conducting 125 the current to the central electrode.

5. A spark plug comprising an integral shell having a relatively long hex on its exterior and an exteriorly threaded chamber at its lower end and an interiorly threaded 130

- chamber at its upper end of greater diameter than said lower chamber, said chambers having a communicating bore having an annular shoulder, an insulating core having a shoulder in juxtaposition to the shoulder of the bore and having its ends projecting into and terminating within said chambers, the bore adjacent to the upper chamber being interiorly threaded, a bushing within said upper chamber and fitting said bore threads for holding the insulating core in position, an insulating plug closing the upper chamber and carrying a rod for conducting the current to the central electrode.
- 5 10 15 20 25 30 35 40 45 50 55
6. A spark plug comprising a one-piece shell having a centrally located bore therein terminating at its upper end in an enlarged chamber, an insulating core within said shell and having an electrode and having its upper end projecting into and terminating within said chamber, and means for closing said chamber and carrying means for connecting the conduit wire with said electrode.
7. A spark plug comprising only the following members: a one-piece shell having a long hex on the exterior thereof and an exterior thread at its lower end and provided with a pair of chambers, one at its upper end and the other at its lower and with interior threads between said chambers, said
- upper chamber having one or more sight openings therein, an insulated core having a central electrode with the upper end of the core projecting into the upper chamber, a bushing engaging the interior threads of the shell for securing the core in place, a terminal carried at the lower end of the shell to form a spark gap, a one-piece insulating closure for the upper end of the shell and having a central rod spaced from the central electrode of the core, means for securing the terminal wire to the plug, and means located in the upper chamber for closing the sight opening.
8. A spark plug comprising a one-piece shell having a centrally located bore therein terminating at its upper end in an enlarged chamber, an insulating core within said shell and having an electrode and having its upper end projecting into and terminating within said chamber, means for closing said chamber and carrying means for connecting a conduit wire with said electrode, said shell having above said bore and around the enlarged chamber an angular formed exterior portion for the reception of a wrench.

Signed at Cleveland, in the county of Cuyahoga, this 28th day of July, 1916.

WILLIAM E. SHERBONDY.
